United States Patent Office

Des. 202,947

Patented Nov. 16, 1965

202,947

CATAMARAN BOAT

Ted O. Jones, Kennydale, Wash., assignor to Hydro Marine Incorporated, Houghton, Wash., a corporation of Washington

Filed Oct. 9, 1964, Ser. No. 32,113

Term of patent 14 years

(Cl. D71—1)

FIG. 1

FIG. 2

FIG. 3

FIG. 4

FIG. 5

FIG. 6

FIG. 1 is a bow on perspective view of a catamaran boat showing my new design;

FIG. 2 is a side elevational view thereof;

FIG. 3 is a front elevational view thereof;

FIG. 4 is a top plan view thereof;

FIG. 5 is a bottom plan view thereof; and

FIG. 6 is a rear elevational view thereof.

The side not shown is a mirror image of the side shown.

I claim:

The ornamental design for a catamaran boat, substantially as shown and described.
